UNITED STATES PATENT OFFICE

2,070,476

CIRCUIT CONTROLLING DEVICE

John Eaton, Schenectady, N. Y., assignor to General Electric Company, a corporation of New York

Application February 4, 1936, Serial No. 62,288

8 Claims. (Cl. 200—81)

My invention relates to circuit controlling devices, more particularly to circuit controlling devices for providing combined automatic and manual control of electrical apparatus such, for example, as electric refrigerators, and has for an object the provision of a simple, reliable and inexpensive device of this character.

Circuit controlling devices of the above type have heretofore been applied to electric refrigerators and provided with means for operating circuit controlling contacts between open and closed circuit positions in accordance with the refrigerator temperature, to maintain a desired mean average temperature, with overload responsive means for opening the contacts to protect the refrigerator motor against excess current, and with manually operable means for opening and closing the contacts at will. Much is yet to be desired, however, in providing a device of this type which is compact in its construction and simple and reliable in its operation. Furthermore, it has been found that the calibration of the overload means may be seriously affected during resetting of the contacts following an overload operation, a considerable strain being imposed on the thermal element during this resetting operation. Accordingly, it is a further object of my invention to provide a circuit controlling device of the above character provided with improved resetting means.

In carrying out my invention in one form, I provide a circuit controlling device having a movable contact operable between open and closed circuit positions to control an electric circuit, tripping means biased for movement to operate the contact to its open circuit position, and restraining means for holding the tripping means against operation, the restraining means including a latch member normally held in one position by the overload means. The overload means is operable in response to predetermined current conditions to release the latch member and thereby permit movement of the latch member and the tripping member, the restraining means being operable during such movement to return the latch member to its normal position upon completion of the tripping operation. Manual means are also provided for returning the tripping member to its normal position after the overload means has returned to restraining relation with the latch member.

For a more complete understanding of my invention, reference should now be had to the drawing in which Fig. 1 is a perspective view of a circuit controlling device embodying my invention;

and Figs. 2, 3, and 4 are fragmentary, elevational views of the device shown in Fig. 1, showing the device in different operating positions.

Referring now to the drawing, I have shown my invention as applied to a circuit controlling device comprising a base member 10 provided adjacent one end with a pair of outwardly extending side plates 11 and 12 and provided adjacent the other end with an outwardly extending end plate 13. Mounted between the side plates 11 and 12, is an expansible bellows 14, one end of which is secured to the base plate 10 and connected to a suitable temperature bulb (not shown) by a tube 15 (Fig. 2). It will be understood of course that the bellows and its associated bulb are filled with a suitable, expansible medium in a manner well known in the art.

As shown, the left-hand end of the bellows 14 is arranged to engage a pivoted lever 16, one end of which is mounted on a pin 17 extending between the side plates 11 and 12. It will be readily understood by those skilled in the art, that expansion and contraction of the bellows 14 is effective to operate the lever 16 about its pivot, and movement of the lever 16 in one direction is opposed by a spring 18, one end of which is secured to the lever 16 and the other end of which is secured to an adjustable member 19 which extends through the base plate 10.

The lever 16 extends through a suitable notch 20 formed in the plate 13 and is connected to one end of a U-shaped spring link 21, the yoke portion of which is engaged by the spring 22, the other end of the spring being secured to the yoke of a U-shaped switch member 23, the arms 35 of which are pivotally mounted on pins 24 (only one of which is shown) extending respectively from suitable lugs which extend outwardly from the end plate 13 in substantially parallel relation with the side plates 11 and 12. As shown, the yoke end of the spring link 21 extends through a suitable notch 25 in the plate 13 and as will be more fully explained hereinafter, the sides of the notches 20 and 25 provide stops for the lever 16 and the spring link 21 respectively. As shown best in Figs. 2, 3, and 4, one arm of the U-shaped switch member 23 i. e. the left hand arm as viewed in Fig. 1 is provided in its lower end with an extending finger 26 which is arranged to engage the plate 13 when the switch member 23 is in its open circuit position, shown in Figs. 3 and 4, so as to provide a stop for the switch member 23.

Extending across the U-shaped switch member 23, is a bar 27 and a pair of insulating members

28 and 29. Although the bar 27 and the insulating members 28 and 29 may be secured to the switch member 23 in any suitable manner, I prefer to provide the arms of the switch member 5 with extending tangs 30, one of which is shown in Fig. 2, which tangs extend through suitable apertures in the members 27, 28, and 29 and may be overturned to secure these members to the switch member 23. Intermediate its ends, the insulating member 29 supports an extending finger 31 which, in turn, supports a bridging switch contact member 32 intermediate its ends. The opposite ends of this bridging contact member are arranged to engage a pair of fixed contacts 33 and 34 which 10 are supported on an insulating block 35 suitably secured to the end plate 13.

Resiliently supported on the insulating block 35 by means of a spring 36, is a bimetallic element 37 which supports a heating winding 38. As 20 shown, the free end of the bimetallic element 37 is arranged to engage a notch in one end of an insulating arm 39, the other end of which is secured by rivets 40 to one arm of a bell-crank lever 41 which is pivotally mounted on a pin 42 25 extending outwardly from the frame. The other arm of the bellcrank lever 41 supports one end of a bimetallic element 43, the other end of the bimetallic element 43 being arranged abuttingly to engage a latch member 44 which is pivotally 30 mounted on a pin 45 extending outwardly from the side plate 12 of the frame. As shown best in Figs. 2, 3, and 4, this latch member 44 pivotally supports one end of a connecting lever 46, the other end of which is provided with a pin 47 extending 35 into a slot 48 formed in a pivoted tripping member 49. This tripping member 49 is pivotally mounted on one of the pins 24 which support the switch member 23 and is provided, as shown, with a slot 50 through which the pivot pin 42 extends, the slot 50 being sufficiently large so that the tripping member 49 is free to move about its pivot without interference from the pivot pin 42.

As shown best in Fig. 1, the side plate 12 is provided with a pair of aligned slots 51 and 52, 45 and a bifurcated operating member 53 is provided having cross members 54 and 55 which extend through the slots 52 and 51 respectively, the bifurcated member straddling the side plate 12 and being guided thereby for longitudinal movement. One leg of the bifurcated member 53 is provided with a transverse slot 56 through which an intermediate portion of the lever 46 extends. This slot 56 also provides for assembly of the bifurcated member 53 on the side plate 12 in 50 slidable relation therewith, the slot 56 being somewhat wider than the cross portion 57 which separates the slots 51 and 52.

The left-hand end of the bifurcated operating lever 53 is provided, as shown, with a knob 58, 60 and a spring 59, one end of which engages the knob 58 serves to bias the member 53 for operation in a left-hand direction, as viewed in the drawing, the lower end of the spring 59 engaging a finger 60 which extends outwardly from the tripping member 49 so as to bias the tripping member for rotation in a counterclockwise direction about its pivot, as viewed in the drawing. The tripping member 49 and the bifurcated 65 operating lever 53 are normally restrained in the position shown in Figs. 1 and 2 by engagement of the pin 47 on the connecting lever 46 with a shoulder 61 formed on one side of the slot 48, the connecting lever 46 engaging the right-hand 70 side of the slot 56 to restrain the bifurcated 75

operating lever 53 against movement in a left-hand direction.

It is now believed that a complete understanding of my invention may be had from a description of the operation of the control device shown. 5 For the purposes of this description it will be assumed that the control device is arranged to control an electric refrigerator of the type having a motor-driven compressor, the bellows 14 being responsive to the temperature of the refrigerator 10 and the circuit controlling contacts being connected in the energizing circuit of the motor. The circuit through the control device may be traced from the connecting lead 62 (Fig. 1) 15 through the fixed contacts 33, the bridging contact member 32, the other fixed contact 34, a conductor 63, the bimetallic strip 37, and the heating winding 38 to the other connecting lead 64. It will thus be seen that the bimetallic strip 37 is arranged to be heated in accordance with the 20 current flowing in the motor circuit, and as will be understood by those skilled in the art, the bimetallic element 43 which is affected only by ambient temperature conditions, serves to compensate for deflection of the bimetallic element 37 25 in response to ambient temperature changes so that the overload tripping means will at all times be responsive to a predetermined value of motor current.

With the control device in the operating position shown in Figs. 1 and 2, it will be seen that the motor circuit is completed through the contacts 33, 32, and 34, and accordingly, the refrigerator is operating to provide a gradually decreasing temperature. When the refrigerator temperature has decreased to the desired value, the bellows 14 will have contracted and the spring 18 will operate the lever 16 in a clockwise direction about its pivot. As the lever 16 moves in this direction, it will be seen that the upper end of the U-shaped spring link will be moved toward the spring 22, and accordingly, the spring 22 will be stressed. As the arms of the spring link 21 move past the line of action of the spring 22, the spring will exert a force on the spring link 45 21 tending to rotate the spring link about its pivot in a clockwise direction, the yoke end of the spring link moving from the position shown to a position in which it engages the other side of the slot 25. Accordingly, the lower end of the 50 spring 22 is moved from the position shown in which it exerts a force on the switch member 23 tending to rotate the switch member in a clockwise direction about its pivot 24 to a position in which the spring 22 exerts a force on the switch member 23 tending to rotate it in a counterclockwise direction about its pivot. The switch member 23 will, therefore, be moved with a snap action to disengage the bridging member 32 from the fixed contacts 33 and 34. The construction 60 and the operation of the mechanism for operating the contacts in response to changes of refrigerator temperature comprise no part of the present invention, and are fully described and claimed in United States Patent No. 1,921,126 65 issued August 8, 1933 to Leonard P. Hutt.

It will be understood of course that consequent to the opening of the circuit controlling contacts, the refrigerator motor will be stopped, and accordingly, the temperature of the refrigerator 70 will increase so as to expand the bellows 14 and upon a predetermined expansion of the bellows 14, the contacts will be operated to the closed circuit position in a manner similar to that described above.

It will now be assumed that with the control device in the positions shown in Figs. 1 and 2, a current of overload magnitude flows in the motor circuit. This current flowing through the bimetallic element 37 and the heating winding 38 so heats the bimetallic element as to cause the free end of the element to move in a right-hand direction, as viewed in the drawing. Accordingly, the bellcrank lever 41 will be rotated in a clockwise direction about its pivot, and the free end of the bimetallic element 43 will move in a left-hand direction out of engagement with the latch member 44. It will be remembered that the tripping member 49 is biased by the spring 59 for movement in a counterclockwise direction about its pivot and since this bias is transferred to the latch member 44 through the connecting lever 46, it will be apparent that as soon as the bimetallic element 43 moves out of engaging relation with the latch member 44, the spring 59 will be effective to rotate the tripping member 49 and the latch member 44, the connecting link 46 being moved upwardly during rotation of these members.

As the tripping member 49 rotates in a counterclockwise direction, a finger 65 formed thereon engages the insulating member 28 carried by the switch member 23 and operates the switch member 23 to the open circuit position shown in Fig. 3.

In Fig. 3, the tripping member 49, the connecting lever 46 and the latch member 44 are shown in the positions which they assumed at the instant immediately following separation of the contacts, and it will be seen that in this position, the angular relation of the shoulder 61 relative to the pin 47 has changed so that the force of the spring 59 transmitted through the operating member 53 to the connecting lever 46 is sufficient to move the pin 47 over the shoulder 61. As soon as the pin 47 moves past the shoulder, the connecting lever 46 is released for movement about its pivotal connection to the latch 44, and accordingly, the spring 59 moves the operating lever 53 in a left-hand direction to the position shown in Fig. 4. During this movement of the operating lever 53, the pin 47 engages the upper side of the slot 48, and a cam action is thereby exerted on the pin 47 which is effective to move the lever 46 downwardly to the position shown in Fig. 4, so as to return the latch member 44 to the position there shown. The pin 17 which extends outwardly from the plate 12, as shown best in Fig. 1, serves as a stop to maintain the latch member 44 in the position shown in Fig. 4.

Operation of the contacts to the open circuit position will of course effect deenergization of the heater 38 and as the bimetallic element 37 cools, it will be apparent that the bimetallic element 43 is free to return to its normal latching position without interference from the latch member 44. Accordingly, the calibration of the control device will not be effected during the resetting operation, since no strain is imposed on either the bimetallic element 32 or the bimetallic element 43. After the bimetallic element 37 has cooled and the bimetallic element 43 has returned to the position shown in Fig. 4, the tripping member may be reset by depressing the switch button 58 so as to move the operating lever 53 in a right-hand direction. This movement of the member 53 will cause the left-hand edge of the slot 56 to engage the connecting lever 46 and rotate the connecting lever in a clockwise direction about its pivot, so as to move the pin 47 in a right-hand direction along the lower edge of the slot 48.

During this movement, the pin 47 exerts a cam action on the tripping member 49, so as to rotate the tripping member in a clockwise direction about its pivot to the position shown in Fig. 2, the pin 47 at the end of the resetting movement passing over the shoulder 61. Since the spring 59 is compressed during this resetting operation, the pin 47 will be retained in engagement with the shoulder 61 by the force exerted on the tripping member and on the lever 46, and accordingly, the parts will be held in the positions shown in Fig. 2 when the push button 58 is released.

Although the latching engagement between the pin 47 and the shoulder 61 is sufficient to prevent movement of the lever 46 and the tripping member 49 by the spring 59, the control device may be manually operated to the open circuit position by simply exerting a sufficient force on the push button 58 in a left-hand direction to force the pin 47 over the crest of the shoulder 61. As soon as the pin 47 is released from the shoulder 61, the spring 59 will assist in moving the tripping member and the connecting lever 46 to the position shown in Fig. 4, whereby the switch member 23 will be operated to the open circuit position.

It will be apparent that my improved control device is entirely trip-free, i. e. operation of the contacts to the open circuit position in response to an overload cannot be prevented by holding the push button 58 in its depressed position. If the push button 58 is so held, the parts will move to the position shown in Fig. 3 upon the occurrence of an overload condition, and the resetting action of the connecting lever 46 in regard to the lever 44 will not take place until the push button 58 is released. The circuit controlling contacts, however, move to the open circuit position shown in Fig. 3.

While I have shown a particular embodiment of my invention, it will be understood, of course, that I do not wish to be limited thereto since many modifications may be made and I, therefore, contemplate by the appended claims to cover any such modifications as fall within the true spirit and scope of my invention.

What I claim as new and desire to secure by Letters Patent of the United States, is:

1. A circuit controlling device comprising contacts one of which is movable between open and closed circuit positions, a tripping member pivotally mounted for rotation to cause operation of said one contact to said open circuit position, a normally restrained latch member, a connecting lever pivotally secured to said latch member, means biasing said lever and said tripping member for rotation about their respective pivots, a releasable connection between said lever and said tripping member for restraining said lever and said tripping member against movement so long as said latch member is restrained, overload means for releasing said latch member whereupon said tripping member rotates in accordance with its bias to operate said one contact and to release said connecting lever, and means responsive to the consequent rotation of said connecting lever in accordance with its bias for returning said latch member to its normal position.

2. A circuit controlling device comprising contacts one of which is movable between open and closed circuit positions, a tripping member pivotally mounted for rotation to cause operation of said one contact to said open circuit position, a normally restrained latch member, a connecting lever pivotally secured to said latch member, means including a single biasing spring for bias-

ing said lever and said tripping member for rotation about their respective pivots, a latching connection between said lever and said tripping member including cooperating cam surfaces for restraining said lever and said tripping member against movement so long as said latch member is restrained, overload means for releasing said latch member whereupon said tripping member rotates in accordance with its bias to operate said one contact, said rotation of said tripping member causing relative movement between said cam surfaces to release said lever for rotation about its pivot, and means responsive to rotation of said lever for returning said latch member to its normal position.

3. A circuit controlling device comprising contacts one of which is movable between open and closed circuit positions, means for operating said one contact between said positions, a tripping member pivotally mounted for rotation to cause operation of said one contact to open position independently of said operating means, a normally restrained latch member, a connecting lever pivotally secured to said latch member, means biasing said lever and said tripping member for rotation about their respective pivots, a releasable connection between said lever and said tripping member including cooperating cam surfaces for restraining said lever and said tripping member against movement by said biasing means so long as said latch member is restrained, overload means for releasing said latch member to permit operation of said tripping member, and manual means for moving said lever to force said cam surfaces out of engagement whereby said tripping member is released for operation independently of said restrained latch member.

4. A circuit controlling device comprising a tripping member having a cam surface thereon, a latch member, a connecting lever having one end pivotally secured to said latch member and its other end engaging said cam surface, means for biasing said lever for movement about its pivot to move said other end along said cam surface, a shoulder on said cam surface engaging said end to restrain said lever against pivotal movement, means biasing said tripping member for movement from a normal position to a tripped position and current responsive means normally restraining said latch member against movement whereby said connecting lever restrains said tripping member against movement, said current responsive means being operable to release said latch member whereupon said tripping member is operated to its tripped position by its biasing means, the relative movement of said tripping member and said connecting lever during said operation releasing said lever from said shoulder for operation about its pivot in accordance with its bias, said cam surface and said lever cooperating during pivotal operation of said lever to return said latch member to its normal position.

5. A circuit controlling device comprising a tripping member having a cam slot therein, a latch member, a connecting lever having one end pivotally secured to said latch member, a pin supported on the other end of said lever and extending within said cam slot, means biasing said lever for movement about its pivot to move said pin along said slot, a shoulder on one side of said slot engaging said pin to restrain said lever against pivotal movement, means biasing said tripping member for movement from a normal position to a tripped position, and current re-

sponsive means normally restraining said latch member against movement whereby said connecting lever restrains said tripping member, said current responsive means being operable to release said latch member whereupon said tripping member is operated to its tripped position by its biasing means, the relative movement of said tripping member and said connecting lever during said operation releasing said pin from said shoulder whereupon said lever is operated about its pivot by its biasing means, said cam slot and said pin cooperating during said pivotal movement of said lever to return said latch member to its normal position.

6. A circuit controlling device comprising a pivoted tripping member having a cam slot therein, a pivoted latch member, a connecting lever having one end pivotally secured to said latch member, a pin supported on the other end of said lever and extending within said cam slot, an operating member arranged to engage an intermediate portion of said lever, a biasing spring arranged to bias said tripping member for movement from a normal position to a tripped position and to bias said operating member for movement in one direction to operate said lever about its pivot, a shoulder formed on one side of said slot engaging said pin to restrain said lever against pivotal movement, overload means normally restraining said latch member against movement whereby said connecting lever restrains said tripping member, said overload means being operable on overload to release said latch member whereupon said tripping member is operated to its tripped position by said biasing spring, the relative movement of said tripping member and said lever during said operation releasing said pin from said shoulder whereupon said operating member moves said lever about its pivot, said cam slot and said pin cooperating during said pivotal movement to return said latch member to its normal position, and manual means for moving said operating member in an opposite direction to move said lever about its pivot and return said pin to its normal engaging relation with said shoulder, said slot and said pin cooperating to return said tripping member to its normal position.

7. A circuit controlling device comprising a pivoted tripping member having a cam slot therein, a pivoted latch member, a connecting lever having one end pivotally secured to said latch member, a pin supported on the other end of said lever engaging said cam slot whereby said lever is moved longitudinally as said members rotate about their respective pivots, an operating member slidable transversely of said lever and having a portion arranged abuttingly to engage said lever, a biasing spring arranged to bias said tripping member for rotation to a tripped position and to bias said operating member for movement in one direction to operate said lever about its pivot, a shoulder in said slot engaging said pin to restrain said lever against pivotal movement, latching means including a thermal element normally restraining said latch member against movement whereby said connecting lever restrains said tripping member, said thermal element when heated being operable to release said latch member whereupon said tripping element is operated to its tripped position by said biasing spring, said lever moving longitudinally as said tripping member rotates to release said pin from said shoulder whereupon said operating member is moved by said spring to operate said lever about its pivot.

- its pivot, said pin engaging a side of said cam slot during said pivotal operation to move said lever longitudinally and return said latch member to its normal position for reengagement with said latching means when said thermal element cools, and manual means for moving said operating member against the bias of said spring to move said lever about its pivot, said pivotal movement being effective when said latch member is restrained by said latching means to return said pin to its normal engaging relation with said shoulder, said pin engaging another side of said cam slot during said movement to return said tripping member to its normal position.
- 15 8. A circuit controlling device comprising a movable control lever, a latch member mounted for movement from one position to a second position, means pivotally mounting one end of said lever on said latch member whereby longitudinal movement of said lever operates said latch member between said positions, current responsive means for normally latching said latch member in said one position, a pivoted tripping member having a cam slot therein shaped to provide a shoulder, means for biasing said tripping member for movement from a normal position to a tripped position, said lever having its other end extending into said slot and engaging said shoulder to restrain said tripping member against movement to said tripped position, an operating member movable to engage an intermediate portion of said control lever, means for biasing said operating member for movement in a direction to rotate said lever about its pivot, said shoulder preventing said rotation of said lever, said current responsive means being effective to release 10 said latch member in response to predetermined current conditions whereupon the biasing force on said tripping member operates said tripping member to said tripped position and thereby operates said control lever longitudinally to move 15 said latch member to said second position, said operation of said tripping member and said control lever releasing said lever from engagement with said shoulder whereupon said operating member moves in accordance with its bias to rotate said control lever about its pivot, and means including said cam slot for moving said lever longitudinally in response to rotation thereof to return said latch member to said one position.
